UNITED STATES PATENT OFFICE.

ISAAC KARPEN, OF CHICAGO, ILLINOIS, ASSIGNOR TO S. KARPEN & BROS., OF CHICAGO, ILLINOIS, A CORPORATION OF WEST VIRGINIA.

CHAIR AND OTHER ARTICLE OF FURNITURE.

No. 924,239.

Specification of Letters Patent.

Patented June 8, 1909.

Application filed March 7, 1908. Serial No. 419,694.

To all whom it may concern:

Be it known that I, ISAAC KARPEN, a citizen of the United States, residing at Chicago, in the county of Cook and State of Illinois, have invented a new and useful Improvement in Chairs and other Articles of Furniture, of which the following is a specification.

My invention relates particularly to chairs and other articles of furniture involving in their construction the use of sides and a seat and a back interposed between said sides.

My primary object is to provide an improved article of furniture, of knock-down construction, which may be crated compactly for the purpose of shipment, which may be readily set up by an unskilled person, and which will, when assembled, afford as substantial a construction as could be desired.

20 The invention is, for convenience, illustrated in its embodiment in an arm-chair, but it will be readily understood that the invention is applicable to rocking-chairs, sofas, etc.

25 In the accompanying drawings—Figure 1 represents a side elevational view of a chair constructed in accordance with my invention; Fig. 2, a rear elevational view, partly in section, of said chair; Fig. 3, a horizontal section taken as indicated at line 3 of Fig. 2; Fig. 4, a broken perspective view showing a portion of one side of the chair and a portion of the back of the chair, illustrating how said parts are adapted to fit together; and Fig. 5, a broken section taken as indicated at line 5 of Fig. 2.

In the construction illustrated, the chair comprises sides A, A¹; an interposed seat A²; an interposed back A³; an adjustable tension-rod A⁴ connecting the sides at or in the vicinity of the seat; an adjustable tension-rod A⁵ connecting the sides at or in the vicinity of the back; and a removable guard, or housing-member, A⁶, serving to conceal 45 the tension-rod A⁵.

Each of the sides A, A¹ preferably comprises legs a, a¹; a lower connecting member, or round, a²; an intermediate connecting member a³; an arm a⁴; and a vertical member a⁵ extending from the arm to the lower cross-member. The rear leg a¹ has an extension a⁶ which extends above the arm.

50 The seat A² preferably comprises a box-frame having side-members a⁷ and front and

rear members a⁸, a⁹ respectively; and a cushion a¹⁰ carried by said box-frame.

The back, in the form shown, comprises a frame, having side-members a¹¹, and top and bottom members a¹², a¹³, respectively; and a back-cushion a¹⁴ carried by the back-frame 60 on the front side thereof.

The seat-frame is equipped at its lateral edges with dowel-pins a¹⁵ which are received in sockets with which the sides of the chair are provided on their inner surfaces; and the 65 lateral edges of the back-frame are equipped with dowel-pins a¹⁶ which enter sockets or holes with which the sides of the chair are provided on their inner surfaces.

The tension-rod A⁴ preferably comprises a 70 pair of right and left threaded bolts a¹⁷, a¹⁸, and a turnbuckle a¹⁹. Each of said bolts passes through an opening in the member a³ of the side of the chair and in the adjacent member a⁷ of the seat-frame, the bolt having 75 a head located outside the member a³. The turnbuckle a¹⁹ is centrally located beneath the cushion of the chair, and is accessible from the lower side of the seat.

The tension-rod A⁵ preferably comprises 80 right and left threaded bolts a²⁰, a²¹; and a centrally located turn-buckle a²² which is disposed in the rear of the back-cushion and in the plane of the back-frame. Each bolt passes through one of the extensions a⁶ and 85 the adjacent member a¹¹ of the back-frame, each bolt having a head engaging the outer lateral surface of the extension a⁶.

The guard, or housing-member, A⁶ comprises preferably a board or strip a²³ of a 90 length to fit snugly between the side-members a¹¹ of the back-frame, said strip having its lower edge provided with a longitudinal slot a²⁴, which extends the length of the strip, thereby enabling the strip to be slipped over 95 the tension-rod to conceal the same from view, as will be readily understood from Figs. 2 and 5.

The manner of assembling the parts of the chair will be readily understood. The side 100 and back are interposed between the sides of the chair, and the dowels are entered in their sockets; after which the bolts forming the tension rods are inserted, and the turn-buckles applied. By means of the turn-buckles tension is applied to the rods, drawing the sides of the chair firmly together, and clamping the seat and back firmly between 105

the sides of the chair. The housing-member A⁶ is then applied, being readily forced into position.

It will at once be understood that the tension-rods provide an exceedingly secure connection between the sides of the chair, and that it is impossible, when the turn-buckles are properly adjusted, for the sides of the chair to spread sufficiently to allow the 10 dowel-pins to leave their sockets. In fact, the clamping action is so secure that there is no possibility whatever of the parts becoming separated. The article of furniture is therefore, as a matter of fact, really more 15 durable than most of the high-class furniture which is not of knock-down construction.

It will be readily understood that the invention is applicable to chairs other than arm-chairs, and to sofas and other like articles of furniture.

The foregoing detailed description has been given for clearness of understanding only, and no undue limitation is to be understood therefrom.

25 What I regard as new, and desire to secure by Letters Patent, is—

1. A knock-down chair comprising sides having arms and rear legs provided with extensions rising above said arms, a seat-frame

interposed between said sides, a back-frame 30 interposed between said extensions, bolts passing through said sides and seat and equipped with a turn-buckle located within the frame of the seat, bolts passing through said extensions and said back-frame, a back 35 carried by said back-frame, and a turn-buckle applied to said last-named bolts in the rear of said back and located in the plane of said back-frame.

2. A knock-down chair comprising sides 40 having arms and rear legs with extensions rising above said arms, a seat interposed between said sides, a back-frame interposed between said extensions, bolts passing through said sides and seat and equipped with a turn-buckle located within the frame of the seat, bolts passing through said extensions and said back-frame, a back carried by said back-frame and located in front of said last-named 45 bolts, a turn-buckle applied to said last-named bolts in the rear of said back, and a housing-member fitted between the sides of said back-frame and having a slot receiving said last-named bolts and turn-buckle.

ISAAC KARPEN.

In the presence of—

R. A. RAYMOND,
A. U. THORIEN.
